Attys.

UNITED STATES PATENT OFFICE.

MILTON L. DODGE, OF NEWBURYPORT, MASSACHUSETTS.

TURN SHOE.

Application filed November 23, 1921. Serial No. 517,200.

To all whom it may concern:

Be it known that I, MILTON L. DODGE, a citizen of the United States, residing at Newburyport, in the county of Essex and State of Massachusetts, have invented new and useful Improvements in Turn Shoes, of which the following is a specification.

This application relates to the manufacture of turn shoes, so-called, and has for its object to provide certain improvements in the process of manufacturing the same for the purpose of reducing the time heretofore necessary for the manufacture of such shoes and at the same time to provide a shoe having the character, style and fit which is desirable.

Ordinarily, in the manufacture of a turn shoe, the upper and the sole are stitched together with the shoe inside-out on the last. In assembling the upper, a box blank is placed between the lining and the cap, and it has been the practice to employ as the box a blank of tempered leather; that is, a leather blank which has been moistened with water until it is soft and flexible. Sometimes, instead of using a blank made of leather, some other material, such as buckram, which may be softened by moisture, is employed. Similarly for the counter stiffener it has been the practice to employ a blank made of tempered or moistened leather. These parts are ordinarily all assembled together on the last and the upper and the sole are stitched together. The leather sole in this operation is likewise moist and relatively flexible, so that, after the lasting and stitching operations have been completed, the last is withdrawn and the shoe turned so that it is right-side-out. The shoe is then relasted, ironed and finished to the last; and the sole, which is more or less wrinkled and soft because of the presence of the moisture, is beaten out with a hand implement such as a hammer. The shoe is then allowed to dry and this drying operation occupies a considerable period of time, frequently from three to eight days. After the drying operation is over, it is then necessary to remove the last from the shoe and the sole is then subjected to a final molding operation in a sole-molding machine to impart to the sole the ultimate shape which it is desired to impart thereto. Even after this has been accomplished, it is again necessary to relast

the shoe to permit the further operations of heelng, buffing, etc., before the completed shoe is ready for shipment. As a result of the series of operations described, it is evident that each pair of shoes requires many days for its manufacture.

All the operations above enumerated, to, and including the beating out operation, must be done while the shoe sole is in temper, and as it is found impracticable to retemper the sole after the upper has been attached and the sole has dried out to any considerable extent, the water necessary for such retempering acting to stain or otherwise injure the upper, all of the operations from the fixing of the sole to the last, to, and including the beating out, must be carried out the same day. As these various operations are performed by several operatives, each one doing a relatively small portion, and as the total time required for all of these operations to be completed for one shoe is considerable, considerable time necessarily elapses after the first operative of the group of operatives engaged in this series of operations begins work in the morning before the last operative of the group has shoes in condition for him to work upon, and the last operative must continue to work at the end of the day long after the first operative has completed his day's work in order to condition all the shoes on which the first operations have been performed that day so that they may be allowed to dry. Thus the possible working day for each of these operatives is materially shorter than the working day of the factory.

The object of the present invention is to shorten the period of time required for the drying of the shoe and to eliminate one of the last pulling and relasting operations in the finishing of the shoe. This relasting operation with the shoe shaping and finishing operations heretofore associated therewith represents a considerable part of the work heretofore done on the shoe while the sole is in temper so that the time interval between the first and last operations when the sole is in temper is greatly lessened by the employment of this invention whereby the possible length of working day for the operatives is considerably increased and made only slightly less than the total length of the factory working day. This, of course, increases the possible output and

the general efficiency of the factory. This I am able to accomplish first by employing initially molded box toe and counter stiffener blanks, and by subjecting the shoe to the 5 molding operation immediately after the shoe has been turned and before it is relasted. Inasmuch as the previously molded box toe and counter stiffener blanks are not moistened or in temper, no time is required 10 for their drying and the only time which is consumed is during the period allotted for the drying of the sole from a few hours to not over a day. As the shoes may be dried 15 off the lasts, the air has free access to the shoe interiors and the drying is therefore much faster than when the shoes are on the lasts while the drying is taking place as heretofore practiced. Also by the use of 20 this invention a much smaller number of lasts is necessary for a given output of shoes since the necessity for the relatively large number carrying shoes of several days' manufacture which are in process of drying 25 at one time when the shoes are dried while on the lasts according to the methods heretofore practiced, is eliminated. The object of the present invention is further achieved by subjecting the shoe to the sole 30 molding operation, after it is turned and before it is dried and relasted, the molding operation occurring while the sole is still in temper and before it is dried.

On the accompanying drawings,—

Figure 1 illustrates a last on which the 35 partially-formed shoe has been stitched to the sole but without the box and the counter stiffener.

Figure 2 shows the shoe after the last has 40 been withdrawn therefrom, the molded box inserted in place, and the molded counter stiffener attached to the sole.

Figure 3 shows the shoe after the turning 45 operation has been completed and the lining has been wiped down to lie inside of the counter stiffener.

Figure 4 is intended to portray the general appearance of the sole of the shoe after the turning operation has been completed.

Figure 5 illustrates the operation of molding 50 the sole of the shoe so as to give it the desired shape.

Figure 6 shows a face view of the sole of the finished shoe.

Figure 7 illustrates a side view of the 55 finished shoe.

In the process of making a turn shoe, I first assemble the sole and the upper on a last with the sole and upper inside-out, and then I stitch them together by the use 60 of the usual machine, the partially made shoe at this time being provided with neither a box toe nor a counter stiffener. The sole, however, is in temper, having been previously moistened. The last is now 65 withdrawn from the shoe and the shoe par-

tially turned as shown in Figure 2. While in this condition, a toe box indicated at 10 is inserted in the toe end of the shoe, the toe box having been initially molded to proper shape before its insertion. It is located 70 between the lining and the cap of the vamp. A previously molded counter stiffener 11 is now secured upon the inner face of the heel end of the sole, as indicated in Figure 2; and, after this has been accomplished, the turning of the vamp is completed and the loose skirt of the lining is tucked and smoothed down inside of the counter stiffener so that the counter stiffener lies between the lining and the quarter. 75 The counter stiffener is provided with a split shank piece such as illustrated in my Patent No. 1,453,924, granted May 1, 1923; and, after the counter stiffener is properly located in place between the lining and the quarter, the loose flap 12 of the shank piece is turned down so as to overlap the inturned edges of the lining and the heel seat flange of the counter stiffener. After these operations have been completed, the partially 80 formed shoe appears substantially as shown in Figures 3 and 4. The turning operation necessarily wrinkles and mars the appearance of the sole, and the sole substantially flat with a slight curvature upward at 85 the toe end of the shoe. The sole, however, is still in temper, and, while it is still moist and before the drying operation has been carried on, the sole is molded by a suitable 90 sole-molding machine, the female mold being shown in Figure 5 at 13 and the male mold being indicated at 14. The co-acting 95 faces of the molds, between which the sole is located, are so shaped as to impart the desired conformation to the entire forepart 100 and shank of the sole by direct pressure between the lines of the inseam stitches. The shank may be rounded or I may impart a diamond-shape thereto as may be desired. In some cases, it is highly desirable that the 105 forepart of the sole should be straight and flat as shown in Figure 7, and that a relatively sharp angle or break between the shank and the forepart should be formed in the shoe as indicated at *a* in Figure 7. 110

After the molding operation has been completed, the shoe is permitted to dry for anywhere from three hours to twenty-four hours to permit the moisture to evaporate from the sole, and the shoe is then relasted 115 for the final finishing operations such as affixing the heel, buffing the edges of the sole etc.

I claim:

1. The method of making turn shoes, 125 which comprises securing an upper to a moistened sole, both inside-out, on a last, removing the last, turning the shoe, and locating a dry previously shaped and molded counter stiffener in proper position in the 130

shoe, then by pressure molding the still wet sole, drying the sole, then reinserting a last, and finishing the shoe.

2. The method of making turn shoes, which 5 comprises securing an upper to a moistened sole, both inside-out, on a last, removing the last, turning the shoe, and locating a dry previously molded toe box and a dry previously 10 molded counter stiffener in their proper positions in the shoe, molding the sole by pressure applied to both faces thereof while the sole is still in temper, drying the sole, and then finishing the shoe.
3. The method of making turn shoes which 15 comprises lasting the shoe wrong side out upon a last, removing the shoe from the last and turning the shoe with the sole in temper, shaping the entire forepart and shank of the shoe to substantially finished shape 20 while the sole is in temper, and finally re-lasting the shoe.

4. The method of making turn shoes which comprises lasting the shoe wrong side out upon a last, removing the shoe from the last 25 and turning the shoe with the sole in temper, molding the entire forepart and shank of the shoe to substantially finished shape by direct pressure between the lines of inseam 30 stitches while the sole is in temper, and finally relasting the shoe.

5. The method of making turn shoes which comprises lasting the shoe wrong side out upon a last, removing the shoe from the last 35 and turning the shoe with the sole in temper, molding the entire forepart and shank of the shoe to substantially finished shape while the sole is in temper, permitting the sole to dry, and finally relasting the shoe.

6. The method of making turn shoes comprising the steps of securing an upper wrong side out to a tempered sole, turning the shoe, molding the sole to the desired shape, allowing the sole to dry so that it will retain its shape, and then relasting the shoe.

7. The method of making turn shoes comprising the steps of securing an upper wrong side out to a sole, turning the shoe, then

molding the entire forepart and shank of the sole, and then relasting the shoe.

8. The method of making turn shoes which 50 comprises securing an upper wrong side out to a tempered sole on a last, removing the last, turning the shoe, inserting a shank piece in the shoe, molding substantially the entire forepart and shank of the sole to 55 substantially finished form, permitting the sole to dry, and then relasting the shoe.

9. The method of making turn shoes which comprises securing an upper wrong side out to a tempered sole on a last, removing the 60 last, turning the shoe, inserting a previously molded counter stiffener and shank piece in the shoe, molding substantially the entire forepart and shank of the sole to substantially finished form, permitting the sole to 65 dry, and then relasting the shoe.

10. The method of making turn shoes which comprises securing an upper wrong side out to a tempered sole on a last, removing the last, turning the shoe, inserting a shank piece in the shoe, molding substantially the entire forepart and shank of the sole to 70 substantially finished form, permitting the sole to dry, and then completing the shoe.

11. The method of making turn shoes 75 which comprises securing an upper wrong side out to a tempered sole on a last, removing the last, turning the shoe, inserting a previously molded counter and shank piece in the shoe, molding substantially the entire 80 forepart and shank of the sole to substantially finished form, permitting the sole to dry, and then completing the shoe.

12. The method of making turn shoes comprising the steps of securing an upper wrong 85 side out to a tempered sole, turning the shoe, and while the sole is still in temper molding substantially the entire forepart and shank of the sole to substantially finished form, then permitting the sole to dry and finishing 90 the shoe.

In testimony whereof I have affixed my signature.

MILTON L. DODGE.
